UNITED STATES PATENT OFFICE

BENJAMIN S. SAMUELS, OF NEW YORK, N. Y.

DESIGN FOR A BOOK-MARKER.

SPECIFICATION forming part of Design No. 23,076, dated February 20, 1894.

Application filed January 9, 1894. Serial No. 496,323. Term of patent 8½ years

To all whom it may concern:

Be it known that I, BENJAMIN S. SAMUELS, a citizen of the United States, residing in the city, county, and State of New York, have invented and produced a new and original Design for a Book-Marker, of which the following is a specification, reference being had to the accompanying drawing, forming part thereof.

10 The leading features of my design for a book marker are—first, emblems or tokens with ornamentalations on the faces thereof, and second, the ribbons which carry the emblems or tokens of a book marker having on the upper ends thereof, a pendant of the form of a star.

In the drawing: A designates emblems or tokens consisting of a cross, anchor and heart.

B designates the ribbons which carry the emblems or tokens. C designates a pendant 20 of the form of a star on the upper ends of said ribbons.

The faces of the tokens or emblems and pendants are ornamented.

What I claim is—

25 The design for a book marker substantially as shown and described.

BENJAMIN S. SAMUELS.
